US00D709450S

(12) **United States Design Patent**
Tanabe et al.

(10) **Patent No.:** US D709,450 S
(45) **Date of Patent:** ** Jul. 22, 2014

(54) **MOTOR**

(71) Applicant: **Panasonic Corporation**, Osaka (JP)

(72) Inventors: **Yuichi Tanabe**, Osaka (JP); **Masahiko Morisaki**, Osaka (JP); **Akihiro Ochiai**, Osaka (JP)

(73) Assignee: **Panasonic Corporation**, Osaka (JP)

(**) Term: **14 Years**

(21) Appl. No.: **29/462,374**

(22) Filed: **Aug. 2, 2013**

(30) **Foreign Application Priority Data**

Feb. 14, 2013 (JP) 2013-002856

(51) **LOC (10) Cl.** 13-01
(52) **U.S. Cl.**

USPC **D13/112**
